L. C. KRUMMEL
MONOLITH CONSTRUCTION

Filed Aug. 23, 1927

UNITED STATES PATENT OFFICE.

LOUIS C. KRUMMEL, OF BROOKLYN, NEW YORK.

MONOLITH CONSTRUCTION.

Application filed August 23, 1927. Serial No. 214,887.

This invention relates to improvements in systems of concrete construction, more especially of the reinforced type, in which pre-cast members are so constructed and arranged that they may be assembled with respect to each other as individuals, and thereafter be connected together to form a monolith.

It has heretofore been proposed to employ pre-cast members in concrete construction work, and the present invention proposes improvements on such constructions in that an improved design and shape of member is provided, which is more readily adapted for interconnection to form the final monolith.

A further feature of the present invention is the construction of the pre-cast members so that they are readily adapted to receive reinforcing elements which serve in the final structure both as reinforcements of the members themselves and to hold the members together.

Another feature of this invention is the particular design of the pre-cast members, which are strengthened by reinforcing elements which have a further function of spacing the connecting elements of the structure.

One form of execution of the present invention has been shown on the accompanying drawings by way of illustration, in which:

Figure 1 is a perspective view of a girder member and two beam members in the partially assembled condition.

Fig. 2 is a transverse section through the girder member of Fig. 1, with parts broken away longitudinally of the beam members to show the connecting elements in position.

Fig. 3 is a transverse section of one of the members on a larger scale showing the system of reinforcing employed.

In these drawings, the construction and assembly of the several members has been illustrated by representing a building wall or abutment 10 to receive the end 11 of a girder member G.

This girder member may be of any shape longitudinally which is well adapted to support the strains placed thereon in use, and in the particular illustration has been rep-

resented as being formed with a central web 12 having at its bottom the outstanding flanges 13 at either side; and at its top being bifurcated to form a channel, as will be more clearly set forth hereinafter. The shape of the bottom flanges 13 conforms to the adopted plan for the girder and is shown as being curved from the wall 10 toward the center, and it will be understood that the other end of this girder may be similarly arranged. From point to point of this girder construction it is provided with notches 14 which are illustrated as passing from side to side of the girder, and being provided with a flat or horizontal floor 15 (Fig. 2) to receive the ends of the beam members.

The upper end of both girder and beam members is bifurcated to form the two walls 16 defining therebetween a channel 17. It is preferred to provide both types of members with the reinforcing bars 18 in the bottom to receive stresses in tension; and to provide similar longitudinal reinforcing bars 19 in each of the side walls 16. A metal saddle member 20, having the shape of a very flat U, is located with its upturned ends 21 within the side walls 16 and serving to stiffen the upper end of the girder or beam member against longitudinal spreading. The floor 22 of the channel 17 is formed during the pre-casting of the particular member; and is substantially horizontal. The saddle members 20 are located from point to point along the length of the particular member and project above this floor 22.

In Fig. 1 it is to be seen that the side walls 16 are deepened adjacent the notches 14 to afford strength at such points; and it will be understood that the reinforcing bars 19 may be looped downward and under the seats for the ends of the beam members as shown in Fig. 2.

The present illustration shows that the floor 22^a of the channel 17 of the girder member is below the floor 22^b of the beam members by a distance substantially equal to the thickness or diameter of the reinforcing bars 23.

As shown in Fig. 2, the ends of the respective beam members B, B^a rest on the floor 15 of the girder member G. The

floor 17 of the beam members B, B^a is depressed above the floor 17 of the notches 14 of the girder member G, as shown in Fig. 2, to a level approximating the level of 5 the floor 17 of the girder member G.

In construction work under this system, the beam and girder members are preformed or pre-cast and are raised to the position for use. A girder member G is seated in its 10 proper position upon walls such as 10, and then the beam members B, B^a are seated with ends resting on the floors 15 of the particular notches 14. Reinforcing bars 23^a are then placed in the channel of the girder 15 member, and are held spaced above the floor 22^a of this member by the thickness of the saddles 20. Similar reinforcing bars 23^b are then located in the channels 17 of the beam members and are held spaced from the 20 floors 22^b of these beam members by the saddles 20 thereof. A concrete grouting is then poured into the respective channels to fill the same around the reinforcing bars 23^a, 23^b and in the interstices between the 25 ends of the beams B, B^a and the walls and floor of the notches 14 of the girder member. When this grouting has set, the whole structure has been joined to form a monolith, and the bars 23^b serve to prevent longitudinal movements of the beams B, B^a with respect to the girder G: and all reinforcing bars join in strengthening the system.

It is obvious that the invention is not limited to the specific illustration set forth, but that it may be modified within the scope of the appended claims.

What is claimed as new is:

1. In a monolith concrete construction, a 40 precast girder having a channel in its upper surface and provided with a notch extending from said channel to the face of the girder, a precast beam having a channel in its upper surface and having an end adapted to 45 be received in said notch, reinforcing bars in said channels, the bar in one of said channels overlying a bar in the other of said channels at the intersection of the channels, and a concrete filling for said channels surrounding and maintaining said bars and joining said beam and girder.

2. In a precast reinforced concrete member, a web and a head, the foot of the web having longitudinal reinforcing bars therein, 55 said head being bifurcated to provide a channel in the upper surface of the member, the bifurcated portions having longitudinal reinforcing bars therein and transverse reinforcing elements extending across the bottom of said channel and exposed therein, said elements being adapted to support a reinforcing bar laid in said channel.

3. In a monolith concrete construction, a precast girder member having a channel in its upper surface and being provided with a notch extending from face to face of the

girder, precast beam members having each 6 a channel in its upper surface and having each an end engaged in said notch so that the beams extend in opposite directions from the girder and have their channels in alignment, the said girder and beam members 7 having longitudinal reinforcing rods in the side walls of the channels and saddle elements extending between said rods to reinforce the members against longitudinal splitting, said saddle elements being exposed in 7 said channel and projecting above the floor thereof, the tops of the saddle elements of the girder member and those of the beam members being located at different levels, a reinforcing bar in said girder channel and a 8 reinforcing bar in said beam channels, said bars being supported at different levels and away from the channel floors by said saddle elements, and a concrete filling surrounding 8 and maintaining the bars and joining said beam and girder.

4. In a pre-cast reinforced concrete member, a web and a head, said head being bifurcated to provide a channel in the upper surface of the member, the bifurcated portions having longitudinal reinforcing bars therein, and U-shaped transverse reinforcing elements extending across the throat of the bifurcation, the ends of said elements being turned upward and embedded in the bifurcated portions.

5. In a pre-cast reinforced concrete member, a web and a head, said head being bifurcated to provide a channel in the upper surface of the member, the bifurcated portions having longitudinal reinforcing bars therein, and transverse reinforcing elements extending across the bottom of said channel and exposed therein, said elements being adapted to support a reinforcing bar laid in said channel.

6. In a pre-cast reinforced concrete member, a web and a head, said head being bifurcated to provide a channel in the upper surface of the member, the bifurcated portions having longitudinal reinforcing bars therein and transverse reinforcing elements extending across the bottom of said channel and exposed therein, said reinforcing elements projecting above the floor of said channel so that they are adapted to support a bar laid in said channel in spaced relationship to the floor of said channel.

7. In a monolith concrete construction, a pre-cast girder having a channel in its upper surface and provided with a notch extending from said channel to the side face of the girder, the bottom of said notch being below the bottom of the channel, a pre-cast beam having a channel in its upper surface and having an end adapted to be received in said notch to substantially fill the same, the floor of the beam channel being

located at a different level from the floor of the girder channel when the two members are assembled together, reinforcing bars in said channels, the bar in one of said channels overlying the bar in the other of said channels at the intersection of the channels, the end of the beam being cut away to leave

the girder channel free for the reception of its respective bar, and a concrete filling for said channels surrounding and maintaining 10 said bars and joining said beam and girder.

In testimony whereof, I affix my signature.

LOUIS C. KRUMMEL.
